[57] CLAIM

The ornamental design for a cocktail table or the like, substantially as shown and described.

DESCRIPTION

FIG. 1 is a view in perspective of the cocktail table showing my new design;

FIG. 2 is a view in top plan of the cocktail table of FIG. 1; and

FIG. 3 is a view in side elevation of the cocktail table of FIG. 1, the opposite side being identical thereto and both ends being identical.
